(57) **CLAIM**

The ornamental design for an umbrella carrier, as shown and described.

DESCRIPTION

FIG. 1 is a front perspective view of an umbrella carrier showing upper and lower sections of strap assembly in a position different than the position shown in FIGS. 3-6; FIG. 2 is a front view of the umbrella carrier of FIG. 1; FIG. 3 is a left side elevational view of the umbrella carrier of FIG. 2. The right side elevational view of the umbrella carrier of FIG. 2 is a mirror image of the view shown in FIG. 3; FIG. 4 is a rear view of the umbrella carrier of FIG. 1; FIG. 5 is a top view of the umbrella carrier of FIG. 2; and, FIG. 6 is a bottom view of the umbrella carrier of FIG. 2. Broken lines indicate structure that is for illustrative purposes only and forms no part of the claimed design. In particular, FIGS. 1-4 show an umbrella in broken lines (inside the carrier with handle sticking out) for illustrative purposes only and FIG. 5 shows broken lines indicating structure that forms no part of the claimed design. Additionally, two of three eyelets, carrying straps, and a ring located below a first unclaimed eyelet are shown in broken lines and therefore form no part of the claimed design. The remaining broken lines are intended to indicate stitching. The difference between the broken lines showing unclaimed subject matter and the broken lines showing stitching is the stitching is represented by equal length dashes, while the unclaimed umbrella, structure, eyelets, carrying straps, and ring are represented by different length dashes.
